RESERVOIR FOUNTAIN BRUSH

Merritt W. Magann, St. Louis, and William A. McElvain, Maplewood, Mo., assignors to Dia-graph-Bradley Stencil Machine Corporation, St. Louis, Mo., a corporation of Missouri

Application November 27, 1946, Serial No. 712,510

2 Claims. (Cl. 15—138)

1

This invention relates to fountain brushes, and with regard to certain more specific features, to valved feed stencil brushes.

This application is a division of our copending application for Fountain Brush, Serial No. 567,922, filed December 13, 1944, eventuated as Patent 2,417,370, March 11, 1947.

Among the several objects of the invention may be noted the provision of a fountain stencil brush in which a valve for controlling ink feed is freely operable from the outside and the arrangement is such as positively to prevent leakage of ink; the provision of a brush of the class described which has an improved operating touch; and the provision of a valved brush of this class which is simple in construction and reliable in operation. Other objects will be in part apparent and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which one of various possible embodiments of the invention is illustrated,

Fig. 1 is a transverse vertical section through the fountain brush of this invention; and,

Fig. 2 is a fragmentary detailed section taken on line 2—2 of Fig. 1.

Similar reference characters indicate corresponding parts throughout the several views of the drawings.

Referring to the drawings, reference character 71 indicates the main body of the fountain brush of this invention. Body 71 is provided at its normally lower end with a threaded counterbore 3 for the removable reception of the threaded ferrule 5 of a standard brush assembly 7. Between the brush assembly 7 (including its ferrule 5) and the top of the counterbore is a packing gasket 9. The body 71 is also provided with an upper threaded counterbore 13. The lower end of an elongate ink reservoir cylinder 41 is threaded into the counterbore 13 and seats against a packing gasket at the lower end of the counterbore. The upper end of this cylinder is closed by a cap 59. The reservoir 41 forms a handle at the other end of body 71 from the brush.

Body 71 is provided with a lateral passage 73 closed at one end by a threaded plug 75 which backs a spring 77. The latter presses upon a guide 79 into which is threaded an extension 81 from an operating stem 83. The operating end

of the stem is located behind a flexible liquid-tight diaphragm, preferably a snap-acting spring disc 85. The margin of this disc is held and sealed in a groove 87 within an enlarged recess 89 formed in the side of the body 71 at the outer end of passage 73 opposite plug 75. Between the extension 81 and the stem 83 is a conical cam 91.

Crosswise of the passage 73 and extending vertically and axially through body 71 is a fluid passage 93, at the lower end of which is a valve seat 95. A valve 97 having a vertically elongate transverse aperture 99 therethrough receiving extension 81 is axially movable in passage 93. This valve is normally biased against valve seat 95 by means of a compression spring 101 backed up by a plug or spring seat 103 in which is a feed opening 105.

Filling of the brush is effected by inverting the reservoir cylinder 41, loading it with ink, and then threading onto it the body 71 while the latter is inverted. Then when the brush is turned upright, the parts are as shown in Fig. 2. The arrangement is such that by pressing upon the disc 85, its snap action forces in the operating stem 83 and causes the cam 91 to raise the valve 97 against the bias of spring 101, thereby to open the valve to allow ink to flow to the brush. Ink enters through the opening 105 and the valve 97 is loose enough in its passage 93 to pass ink around it. The springs 77 and 101 return the parts to the closed position when pressure is released from the snap-acting disc 85. Disc 85 then springs back to the position shown in Fig. 1.

Leakage of ink around operating stem 83 to the outside of the body 71 is positively prevented by the seal between spring disc 85 and the body 71. No packing is necessary around stem 83 to prevent leakage of ink, consequently stem 83 may be made freely slideable within cross passage 73 so as to provide for an improved operating touch. Not only does the invention provide for better touch by free action of the stem 83 without leakage around it, but it provides for snap action by means of the disc 85, and thus provides a tactical signal that the valve has been operated to the proper extent.

It will be understood that valve 97, instead of having a loose fit in passage 93, may have a tighter fit therein and be vertically splined to form passages for ink flow. It will also be understood that the snap-acting disc 85 is generally made of spring metal, but other material such as plastic, rubber, or the like, may be used. In view of the above, it will be seen that the

several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

We claim:

1. A fountain brush comprising a body having a brush at one end and detachably fitted with an elongate reservoir forming a handle at its other end, said body having a fluid passage therethrough from its reservoir end to its brush end and a lateral passage therethrough from one side to the other intersecting said fluid passage, a valve seat at the brush end of the fluid passage and a spring seat at the reservoir end of said fluid passage, the spring seat having an opening for flow of fluid from the reservoir into the fluid passage, said body being formed with an enlarged recess at the outer end of the lateral passage at one side of the fluid passage, a valve slideable in the fluid passage toward and away from the valve seat between a closed position wherein one end of the valve engages the valve seat and an open position where said one end of the valve is away from the valve seat, a spring located in the fluid passage between the other end of the valve and the spring seat at the reservoir end of the fluid passage biasing the valve to closed position, said valve being of such length as to intersect said lateral passage in either open or closed position, and being of such cross-section as to allow flow of fluid around the valve when open, an operating stem slideable in the lateral passage on the side of the fluid passage toward said recess, said stem having a tapered cam portion at its inner end and a reduced extension which reaches from the smaller end of the tapered cam portion loosely through a transverse cam-receiving aperture in the valve, a guide on the end of said extension slideable in the lateral passage on the other side of the fluid passage, a spring in the lateral passage reacting against the guide from a plug closing the lateral passage and biasing the operating stem to a released position projecting out into said recess, and a snap-acting spring disc located in said recess covering and engaging the outer end of the operating stem and having its margin sealed in a groove around said recess.

2. A fountain brush comprising a body having a brush at one end and detachably fitted with an elongate reservoir forming a handle at its other end, said body having a fluid passage therethrough from its reservoir end to its brush end

and a lateral passage therethrough from one side to the other intersecting said fluid passage, a valve seat at one end of the fluid passage and a spring seat at the other end of said fluid passage, the spring seat having an opening for flow of fluid, said body being formed with an enlarged recess at the outer end of the lateral passage at one side of the fluid passage, a valve slideable in the fluid passage toward and away from the valve seat between a closed position wherein one end of the valve engages the valve seat and an open position where said one end of the valve is away from the valve seat, a spring located in the fluid passage between the other end of the valve and the spring seat at the reservoir end of the fluid passage biasing the valve to closed position, said valve being of such length as to intersect said lateral passage in either open or closed position, and being of such cross-section as to allow flow of fluid around the valve when open, an operating stem slideable in the lateral passage on the side of the fluid passage toward said recess, said stem having a tapered cam portion at its inner end and a reduced extension which reaches from the smaller end of the tapered cam portion loosely through a transverse cam-receiving aperture in the valve, a guide on the end of said extension slideable in the lateral passage on the other side of the fluid passage, a spring in the lateral passage reacting against the guide from a plug closing the lateral passage and biasing the operating stem to a released position projecting out into said recess, and a snap-acting spring disc located in said recess covering and engaging the outer end of the operating stem and having its margin sealed in a groove around said recess.
